US00D961584S

(12) **United States Design Patent** (10) **Patent No.:** **US D961,584 S**
(45) **Date of Patent:** **** Aug. 23, 2022**

(54) **ELECTRONIC WATCH DEVICE**

(71) Applicant: **T-Mobile USA, Inc.**, Bellevue, WA (US)

(72) Inventors: **Christopher Painter**, Kirkland, WA (US); **Andre Sacaguti**, Sammamish, WA (US); **Aaron Takeshi Sisneros**, Oakland, CA (US); **Maikel Faltaous**, Renton, WA (US); **Jeffrey Scott Croyle**, San Francisco, CA (US)

(73) Assignee: **T-Mobile USA, Inc.**, Bellevue, WA (US)

(**) Term: **15 Years**

(21) Appl. No.: **29/761,517**

(22) Filed: **Dec. 9, 2020**

(51) LOC (13) Cl. **14-02**

(52) U.S. Cl.

USPC **D14/344**; D10/32

(57) **CLAIM**

The ornamental design for an electronic watch device, as shown and described.

DESCRIPTION

FIG. 1 is a perspective view of an electronic watch device taken from the top, right, and front, showing our new design in an environment of use;

FIG. 2 is a perspective view of the electronic watch device taken from the top, right, and front;

FIG. 3 is a perspective view of the electronic watch device taken from the top, left, and back;

FIG. 4 is a front elevation view of the electronic watch device of FIG. 2;

FIG. 5 back elevation view of the electronic watch device of FIG. 2;

FIG. 6 is a right elevation view of the electronic watch device of FIG. 2;

FIG. 7 is a left elevation view of the electronic watch device of FIG. 2;

FIG. 8 is a top plan view of the electronic watch device of FIG. 2; and,

FIG. 9 is a bottom plan view of the electronic watch device of FIG. 2.

The dashed broken lines showing portions of the electronic watch device form no part of the claimed design. The dashed broken lines showing a watch band are for the purpose of illustrating environment and form no part of the claimed design. The shade lines in FIGS. 1, 2, and 8 show transparent or reflective surfaces and are not representative of surface ornamentation.

1 Claim, 7 Drawing Sheets
